(No Model.)

E. E. SPENCER.

JACK FOR HEEL BURNISHING MACHINES.

No. 310,470.

Patented Jan. 6, 1885.

UNITED STATES PATENT OFFICE.

EDWARD E. SPENCER, OF NEW YORK, N. Y.

JACK FOR HEEL-BURNISHING MACHINES.

SPECIFICATION forming part of Letters Patent No. 310,470, dated January 6, 1885.

Application filed October 30, 1884. (No model.)

To all whom it may concern:

Be it known that I, EDWARD E. SPENCER, a citizen of the United States, residing at New York, in the county and State of New York, 5 have invented new and useful Improvements in Jacks for Heel-Burnishing Machines, of which the following is a specification.

This invention relates to an improvement in jacks of that class which consist of a heel- 10 support, a clamping-bar, and a cam-lever for actuating the clamping-bar.

My improvement consists in the combination, with the heel-support, the clamping-bar, and the cam-lever, of a yielding friction-stop which 15 serves to retain the cam-lever in its locking position against the jar of the burnisher.

In the accompanying drawings, Figure 1 is a sectional side elevation of a jack provided with my friction-stop. Fig. 2 is a transverse 20 section in the plane $x x$, Figs. 1 and 3. Fig. 3 is a horizontal section in the plane $y y$, Fig. 2.

Similar letters indicate corresponding parts.

In the drawings, the letter A designates the heel-support of a jack, such as is in common 25 use in heel-burnishing machines known as "Tapley's heel-burnishers." B is the clamping-bar, which is exposed to the action of a spring, C, that has a tendency to throw the clamping-bar back. D is the cam-lever, which 30 serves to move the clamping-bar forward, so that the same acts upon the heel and presses the same firmly up against the heel-support A.

The lever D has its fulcrum on a pivot, a, which has its bearings in lugs b, secured to or cast 35 on an arm, c, extending from the heel-support. The cam portion d of the lever D is made in the form of a segment, and it extends through a slot, e, in the clamping-bar. By moving the lever up to the position shown in the drawings 40 the clamping-bar is moved forward so as to clamp the heel; but when the machine is in operation the jar produced by the burnisher is liable to cause the lever to sink down in the direction of arrow 1, Fig. 2, and the heel be- 45 comes loose.

For the purpose of retaining the cam-lever in its clamping position against the jar of the machine, I have applied a friction-stop, E. In the example shown by the drawings this friction-stop consists of a button, f, the shank 50 of which screws into a lug, g, projecting from a plate, h, which is retained in position by a pin, i. This pin is firmly secured in the head j, which forms the bearing for the clamping-bar B, and round it is wound a spring, k, the 55 tension of which can be regulated by a nut, l, fitted on the outer end of the pin i. The head of the button f is faced with leather or other equivalent material, and by the action of the spring k this head is depressed upon the convex surface of the cam d. By adjusting the tension of the spring k the pressure exerted by the button f upon the convex surface of the cam d can be so regulated that the cam-lever 60 D is securely retained in its locking position. 65 The pressure of the button f is yielding, so that by applying sufficient force the cam-lever can be moved from its locking position to its unlocking position, and vice versa, without compelling the person tending the machine to 70 raise the button or to perform any motion not required in the ordinary burnishing-machine.

It will be readily seen by any skilled mechanic that the form of the yielding friction-stop can be changed in various ways, and I do 75 not wish to confine myself to the precise form shown in the drawings.

What I claim as new, and desire to secure by Letters Patent, is—

The combination, with the heel-support A, 80 the clamping-bar B, and the cam-lever D, of a yielding friction-stop adapted to bear against the cam-lever, substantially as described.

In testimony whereof I have hereunto set my hand and seal in the presence of two subscribers.

EDWARD E. SPENCER. [I. S.]
